UNITED STATES PATENT OFFICE.

THEODORE F. NOVY, OF CHICAGO, ILLINOIS.

MOLD.

1,201,613.

Specification of Letters Patent. Patented Oct. 17, 1916.

Application filed July 12, 1915. Serial No. 39,259.

To all whom it may concern:

Be it known that I, THEODORE F. NOVY, a citizen of the United States, and resident of Chicago, in the county of Cook and State 5 of Illinois, have invented certain new and useful Improvements in Molds, of which the following is a full, clear, and exact specification.

This invention relates to improvements in 10 molds for columns formed from any plastic material, but preferably from reinforced cement, formed in sections from sheet metal, strengthened by means of longitudinal angle bars and surrounding iron rings at intervals 15 of the length thereof, the construction of which has heretofore been such that the column is defaced by raised seams due to improperly constructed joints, and which for their assembling and dismemberment 20 necessitating objectionable loss of time and labor.

The object of my invention is to provide 25 a sectional mold for columns including a column head, the construction of which is such that it may be repeatedly used, quickly assembled in its operative position for molding a column in place, and that its joints shall be so formed and united as to provide for a perfectly close fit against each other, 30 tight enough to prevent leakage of liquid cement therethrough forming seams, which mold is provided with means rigidly maintaining it against both expansion and contraction, and is adapted to be assembled and 35 disassembled in the quickest possible time by any ordinary unskilled workman, and yet be of maximum lightness, strength and durability.

A further object of my invention is to 40 provide a sectional mold formed from sheet metal suitably braced and strengthened with means whereby it may be adjusted for molding columns, and concurrently therewith a column head therefor, of varying sizes, that 45 is to say varying in diameter, and which is also adapted for the molding of columns in place differing in height.

With these ends in view, my invention finds embodiment in certain features of 50 novelty in the construction, combination and arrangement of parts by which the said objects and certain other objects are attained, all as hereinafter fully described with reference to the accompanying drawings, and 55 particularly pointed out in the claims.

In said drawings: Figure 1 is an elevation of a mold for columns in which my invention finds embodiment, with the sustaining frame therefor shown in section. Fig. 2 is an enlarged detail section of the ring at the 60 upper end of the column section of the mold, and the bracket forming the base support for the column head of the mold. Fig. 3 is a vertical section of a modification of the joints of the column portion of the mold. 65 Fig. 4 is a top plan view of the frame for sustaining the column head portion of the mold in its operative position. Fig. 5 is an enlarged detail section of the sustaining frame of the mold showing the means for 70 connecting it with the column head portion of the mold. Fig. 6 is an enlarged vertical transverse section through a portion of the 75 column head and column of the mold. Fig. 7 is an enlarged detail section thereof more clearly showing the means by which their 80 several parts are connected and adjusted. Fig. 8 is an enlarged elevation of the mold taken on a line at a right angle to the view thereof shown in Fig. 1. Fig. 9 is a detail 85 transverse section taken on the line 9-9 of Fig. 1. Fig. 10 is a detail section taken on the irregular line 10-10 of Fig. 9. Fig. 11 is a top plan view of the column section of the mold taken on the line 11-11 of Fig. 6. Fig. 12 is a transverse section taken on the 90 line 12-12 of Fig. 1. Fig. 13 is a detail showing the clamp in side elevation in its operative position, and Fig. 14 is a top plan view of the sectional column showing a 95 modified means for adjusting it for forming columns of differing diameters.

Similar characters of reference indicate 95 the same parts in the several figures of the drawings.

An important consideration in the construction of molds for columns and heads for unlimited repeated use is that their body portion shall be constructed of galvanized 100 sheet iron of minimum thickness consistent with strength, rigidity and durability. In this connection it is therefore proper to observe that with the use of the strengthening and connecting devices for locking and sustaining the mold of my invention in its operative position, the body portion of both the column and head forming members of my mold may be, and are in practice formed from galvanized sheet iron as thin as twenty gage, and with the result that this thin- 105

ness of sheet iron furnishes a means, as will hereinafter be described, for adjusting the mold of my invention for producing different sizes of columns.

5 The body of the column mold may and is shown to be in two lengths 15 and 16, one of which lengths telescopes in the other as indicated at 17, and with a fit so close that owing to the thinness of their metal, the 10 molded column opposite their joint will be seamless, and are divided longitudinally into two semi-circular sections, reinforced (see Figs. 1, 8 and 9) respectively by means of detachable angle iron bars 19 and 20 extending longitudinally thereof.

15 As a means for preventing the meeting edges of the opposing sheet metal sections from forming either a longitudinal raised bead or groove in the molded column, one 20 section is provided with a longitudinal shoulder 22 and a seat 23 for the edge of the opposing section formed by bending the metal thereof outwardly at a right angle while the opposing sheet metal section is 25 bent upon itself as indicated at 24 so that when held against the shoulder 22, in contact with the seat 23, the inner surface of the mold will be substantially continuous notwithstanding its sectional construction. To 30 provide against the possibility of the cement being forced between the joint formed by these meeting edges when subjected to unusual or excessive pressure, the opposing sections of the column mold are also respectively provided with flanges 25 and 26 projecting between and across the opposing surfaces of and whereby they may be clamped between the angle bars, as hereinafter described, one of which flanges terminates at 35 the outer edge of the angle bars, and the other some distance outwardly therefrom whereby it may be bent over the other flange and the edge of the angle bar adjacent thereto as indicated at 27, thereby capping, and 40 to that extent furnishing a seal closing the outer end of the opposing joint.

45 Flanges 25 and 26 (see Figs. 10) are provided with registering open slots 21, and the angle irons 19 and 20 with registering 50 perforations through which to project a bolt 28, provided at one end with a head 29, and at its opposite end with a hook 30 bent therefrom, opposed by a wedge 31 for drawing the angle irons toward each other, and 55 thereby clamping the flanges 25 and 26 between them tight enough to form a water tight joint, and to which end the wedge is supported by the bolt, and tightened between opposing bearings formed by the hook. 60 and the surface of the angle iron adjacent thereto. As shown in Fig. 1, a number of these bolts may be employed at intervals sufficiently frequent to insure such a water tight joint throughout the length of the two 65 sections, and of such other and further sec-

tions as may be desirable or necessary for the purpose of the column to be molded therefrom.

The sectional column mold above described, is reinforced a short distance below its upper end by means of a correspondingly sectional angle iron ring 32, secured thereto by means of rivets 33 counter-sunk in the inner surface of the mold sections, the outwardly projecting flange of these reinforcing angle 75 irons being also provided at suitable intervals with elongated perforations 33^a (see Fig. 11) through which to project bolts 34.

The body of the column head member for the mold in which my invention finds its embodiment is also constructed from thin sheet metal 35 of the character before described for the column mold, and like the latter is divided vertically^b (see Figs. 6 and 7) into two jointed sections 36 and 37, to the upper 80 edges of which is secured a sheet metal ring 38 by means of rivets 39, and reinforced by an angle iron consisting of sections 40 and 41 secured to the ring by rivets 42, which, together with the rivets 39 are counter-sunk 90 in the inner surface of the collar.

95 Seated on the angle iron 33 and detachably secured thereto by bolts 43 is a sectional angle iron to which is secured by means of counter-sunk rivets 44 a sectional collar 45, the depth of which is about half that of the sections 36 and 37 of the column head mold, and which in its operative position seats at its bottom edge on the bracket 33. The sectional collar 45 not only serves 100 to strengthen and maintain the column head sections against expansion, but furnishes a bearing surface and a support maintaining the upper edge of the column mold in closely fitting contact with the bottom edge of the 105 column head mold, and whereby the column and head members of the mold may be detachably, rigidly connected and suspended from a suitable super-structure of wood 110 hereinafter described.

115 For removably connecting, adjusting and locking the column mold 15 to the column head mold 35, bracket plates 46 and 47 are respectively externally secured toward the upper end of the column head mold 35, and to the sectional collar 45 at the opposite sides thereof by means of rivets 48—48 counter-sunk in the inner surfaces of both of these members, the outwardly projecting ends of which brackets are perforated for the reception of a screw-threaded bolt 49 passing therethrough, provided with a nut 50.

120 As a means for preventing the lateral expansion and bulging of the thin walls of the column mold from the weight, and particularly from the force of impact imparted thereto by the gravity feed of, and the usual ramming down of the concrete in the mold, my invention includes the employment of 125 detachable clamps of a very cheap and yet 130

novel construction, adapted to encircle the column mold at such intervals of its length as may be necessary to these ends.

- The clamp above referred to (see Figs. 1, 12 and 13) consists of opposing segmentally curved flat metal bars 51-52, spaced apart at their opposing ends and connected at one side by curved bars 53-54, respectively rigidly secured thereto by rivets 55-55, the 10 meeting ends of which bars are hinged by overlapping their ends and pivotally connecting them by means of a rivet or bolt 56, the ends of the bars at this point being spaced apart to straddle the longitudinally 15 reinforcing angle irons for the column mold. Secured at a point shortly removed from the opposite end of the curved bar 52 by means of rivets 57-57 is an outwardly curved bar 58, overlapped at its free end by 20 a bar 59 hinged to the bar 58 by means of a rivet or bolt 60. The opposite end of the bar 59 overlaps a curved hand lever 61, which at this point is provided with a series of perforations 62-62 for the reception of 25 a bolt or screw 63, and thereby providing a means for successively compressing the walls of the mold to force out bends, and other irregularities therein, and conform the walls to the circular contour of the opposing bearing 30 surfaces of the clamp. The lever 61 is provided at its end with a perforation 64, and the curved bar 51 with a plurality of perforations 65, whereby when the clamp is tightened upon column molds differing in 35 diameter, the lever may be locked in its operative position by moving its perforations 64 to register with one or the other of perforations 65 as may be, on projecting a wire nail or other pin therethrough.
- 40 In Fig. 14 is shown a modification in the form of the joint connecting the opposing sections of the column mold, and whereby the flexibility of the thin sheet metal from which the sections are formed is utilized for 45 adjusting the mold to a smaller size of column, and to which end one of the mold sections 66 is normally smaller than the opposing section 67, as indicated by dotted lines in Fig. 14, and sprung into locked engagement along one of its longitudinal edges with the smaller section 66.
- For forming a close joint between, and at the same time locking the opposing sections together at one edge while springing the 55 larger section of the mold inwardly to the smaller sized section, the sheet metal of the section 66 for forming one-half of the smaller sized column is first bent backwardly upon itself at 68, thence outwardly at 69, 60 and then at a right angle 70, thereby forming a channel iron, one flange of which formed by the bend 68 is adapted to be projected into a recess formed by an outward bend 71, whence the metal is bent at a right angle 65 thereto, as indicated at 72, and thereby to
- the form of an angle iron fitting the before described channel iron in the smaller mold section 66.
- The bends just described not only provide for maintaining a close contact between the edges of the two sections, and a substantial continuity of their inner surfaces, but to provide a hinge connection sustaining one side of the sectional mold in its operative position, while springing the larger section to locked engagement at the opposite side with the smaller section, and at which point the sheet metal of the section 67 is bent backwardly upon itself as indicated at 73, thence outwardly at 74 and at a right angle at 75 to precisely the same form as the edge of the smaller section 66 is bent at the opposite side of the mold. On the other hand opposing the construction last described the metal of the smaller section is bent outwardly at 76 and provided with a flange 77 to precisely the same form as the edge of the larger section at the opposite side of the mold to form a lock joint on compressing the outer section from the position indicated in dotted lines to that shown in the full lines. In short the modification shown in Fig. 14 provides a means by which a larger section of the column mold may be bent to form the continuation of an opposing smaller section for the purposes of reducing the diameter or size of a column without having both sections therefor normally of the same size. It will now be observed in this reduced size of mold, section 100 76 necessarily forms less and section 67 more than one-half of the mold, the circular form of which is produced and maintained by the reinforcing clamps when correspondingly adjusted, and this owing to the fact that the 105 construction of the clamps provides for their adjustment to two circles differing in diameter, and this is none the less true when the section 67 is moved to its locked position with the section 66 by means of the adjusted clamp, or is adjusted thereto following the bending of section 67 by hand to its locked position with the section 66.
- For locating and sustaining column molds for concrete in their operative position, it 110 has heretofore been the practice to drive nails at frequent intervals therethrough into the false wood work for the concrete ceiling or floor of the structure of which the column is a part, and which is objectionable not only because of the injury to the mold for repeated subsequent use, and the time and difficulty of detaching the flooring of the false wood work therefrom, but for the further and more important reason that the 115 surface of the column or column head, as may be, is marked and marred by the nail heads and not infrequently broken when detaching the mold. As a means for avoiding these objections the false wood ceiling or 120

floors 78 (see Fig. 1) is supported by an open frame consisting (see Fig. 4) of side bars 79-79 connected by, and bars 80-80 extending at a right angle thereto, and with bars 81 at each of its four corners to the inner surfaces of which are secured angle irons 82-82 projecting inwardly therefrom in vertical arrangement forming seats for the sectional flange 40 and 41 of the reinforcing ring for the column head, and in its absence for the flanges of the angle irons 33 at the upper end of the column mold, and whereby the column head mold, or the column mold as may be, is centered and suspended from the adjacent false flooring of the false wood work, and so that a close joint may be formed between the column and the under-surface of the concrete ceiling or floor.

20 As a means for preventing the accidental lifting of the column head mold and the upper section of the column mold as may be, from forcing the lower column mold section upwardly, there may be nailed to the superstructure a flat, preferably sectional ring 83, either of metal or wood, projecting over and against the opposing surface of the reinforcing angle iron sections 40 and 41.

Having described my invention what I claim and desire to secure by Letters Patent is:

1. A structure for the purposes described comprising in combination a column mold consisting of longitudinal sections formed from sheet metal, the opposing edges of which sections overlap each other, outwardly projecting flanges bent from said sections adjacent their overlap, detached angle irons between which opposing flanges of each section are projected, said angle irons and flanges being provided at intervals of their length with perforations registering with each other, a bolt passing therethrough, provided with means for tightening the joints between the flanges and the angle irons.

2. A structure for the purposes described comprising in combination a column mold, consisting of longitudinal sections formed from sheet metal, provided with outwardly projecting flanges bent therefrom, angle irons between which opposing flanges are projected, said angle irons and flanges being provided at intervals of their length with perforations, a bolt passing therethrough provided at one end with a head, and bent at its opposite end, and a wedge interposed between the bent end of the bolt and the angle iron adjacent thereto for clamping the flanges between the angle irons sufficiently to produce a water tight joint therefor.

3. A structure for the purposes described comprising in combination a column mold, consisting of longitudinal sections formed

from sheet metal, provided with outwardly projecting flanges bent therefrom, angle irons detachable therefrom, between which the opposing flanges of said sections are projected, said flanges and angle irons being provided at intervals of their length respectively with open slots and perforations registering with each other, a bolt passing therethrough, provided at one end with a head and at the opposite end with a bend, and a wedge for clamping the angle irons to and tightening the joint between the flanges projecting between the bend in the bolt and the surface of the adjacent angle iron, whereby on loosening the wedge, the sections may be removed from the bolt, and the latter retained as a connection between the angle irons.

4. A structure for the purposes described comprising in combination a column head mold consisting of longitudinal overlapping sections formed from sheet metal provided with outwardly projecting flanges bent therefrom, detachable angle irons between which the opposing flanges of the column head are projected, and means for removably clamping and tightening the joint between said flanges and angle iron.

5. The combination of a column mold, a column head mold, a collar detachably secured to the column mold, and forming a lateral support for the column head mold, each consisting of longitudinal sections formed from sheet metal provided with outwardly projecting alined flanges bent therefrom, detached angle irons between which said opposing flanges are projected, and means at intervals of the length thereof adapted for tightening the joint of said flanges between said angle irons.

6. A structure for the purposes described comprising in combination a column mold and an outwardly projecting reinforcing ring secured toward the upper end thereof, a collar seated upon said ring provided with a reinforcing ring likewise seated upon said ring, a bolt detachably connecting the reinforcing ring of the collar to the reinforcing ring of the column mold, a column head mold supported by said ring and seating against the end of the column mold, bracket bearings respectively fixed to said ring and to the column mold, a screw-threaded bolt connecting said brackets for tightening the column head mold on its seat and against the ring, which said column mold, ring and column head mold consist of longitudinal sections formed from sheet metal, and are provided with overlapping joints, and means for maintaining water tight joints between opposing sections thereof.

7. In a structure for the purposes described, comprising in combination a column head mold consisting of longitudinal

sections formed from sheet metal provided with water tight joints between each section, sectional reinforcing angle irons at the upper portion thereof conforming thereto and projecting outwardly therefrom, a surrounding structure provided at intervals with angle irons in vertical arrangement projecting in the path of said reinforcing ring, and thereby forming the support for the column head mold, a flat sectional ring temporarily secured to said surrounding structure projecting over and providing a

stop maintaining said mold from an upward movement and closing the opening between the mold and said surrounding structure. 15

In witness whereof, I have hereunto set my hand and affixed my seal, this 26th day of June, A. D. 1915.
